DESIGN.

—o—
H. HUNT.

CARPET.

No. 18,158.

Patented Mar. 6, 1888.

UNITED STATES PATENT OFFICE.

HENRY HUNT, OF GREENVILLE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 18,158, dated March 6, 1888.

Application filed January 26, 1888. Serial No. 262,088. Term of patent 3½ years.

To all whom it may concern:

Be it known that I, HENRY HUNT, of Greenville, New Jersey, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design.

My design consists of a combination or grouping of conventionalized or geometrical

flower and leaf forms with simpler geometrical figures, all connected and unified by a conventionalized or geometrical stem-work. The various figures, as well as the connecting stem-work, are angular in outline or appearance. Repeated here and there over the surface of the carpet and between the conventionalized plant forms are small geometrical figures.

What I claim as new, and desire to secure by Letters Patent, is—

The design for carpets, consisting of the design substantially as shown.

HENRY HUNT.
